CLOCK

Otto H. Maser, Chihuahua, Mexico

Application February 4, 1941, Serial No. 377,384

5 Claims. (Cl. 58—125)

This invention relates to clock construction, the primary object of the invention being to provide a clock embodying hands movable transversely over a dial of rectangular construction, thereby providing a timepiece which is exceptionally adapted for use on the instrument boards of motor vehicles, aeroplanes or the like.

An important object of the invention is to provide a device which is used in conjunction with the usual clock mechanism, and connected with the hour and minute hand shafts thereof, whereby rotary movement of said shafts will be converted into right line movement, to accomplish the purpose of the invention.

A further object of the invention is to provide a clock for the instrument board of vehicles, wherein the time may be determined at a glance.

With the foregoing and other objects in view, which will appear as the description proceeds, the invention resides in the combination and arrangement of parts and in the details of construction hereinafter described and claimed it being understood that changes in the precise embodiment of the invention herein described, may be made within the scope of what is claimed, without departing from the spirit of the invention.

Referring to the drawings:

Figure 1 is an elevational view of the device.

Figure 2 is a sectional view through the housing or body portion of the device.

Figure 3 is a sectional view through the housing or body portion of the device taken at right angles to Figure 2 along the line 3—3, illustrating the mechanism in plan.

Figure 4 is a sectional view taken on line 4—4 of Figure 2.

Figure 5 is a perspective view disclosing a portion of one of the cams, and the end of one of the operating arms, as contacting therewith.

Referring to the drawings in detail, the reference character 5 designates the housing or case which is preferably rectangular in formation, the housing being of a depth to accommodate the usual clock mechanism, indicated generally by the reference character 6.

The reference character 7 designates the shaft on which the minute hand of the clock mechanism is usually mounted, and the reference character 8 designates the shaft on which the hour hand of the usual clock mechanism is mounted. For the sake of convenience, the shaft 7 will be referred to throughout the specification as the minute hand shaft, while the shaft 8 will be referred to as the hour hand shaft.

5   Mounted on the minute hand shaft 7, is a cam 9, that is secured to the shaft to rotate therewith. A bell-crank lever indicated at 10 is mounted on the shaft 11 extending through the forward compartment of the case or housing 5, the bell-crank lever having a right angled end or finger 12 that normally rests on the edge of the cam 9, as clearly shown by Figure 5 of the drawings. One arm of the bell-crank lever 10 extends downwardly, where it has pivotal connection with the link 12' that is pivotally connected at one end of the segmental gear 13. A pulley indicated by the reference character 14 is mounted within the case or housing, and is provided with a gear 15 that meshes with the segmental gear 13, to the end that movement of the segmental gear 13 will rotate the pulley 14 in the direction of the arrow, under normal conditions. The pulley 14 is grooved so that the cable 16 which has one end 10 thereof secured to the pulley 14, will be guided in its movements over the pulley. The cable 16 operates through the guide 17 formed in the bracket 18 that is mounted within the casing. The cable is connected with the arm 19 which is provided with a base 20 formed with bores to accommodate the rods 21 of the supporting track, with the result that as the cable 16 is wound on the pulley 14, the arm 19 will be moved in a right line direction. The minute hand of the clock is indicated by the reference character 21', and is formed at the outer end of the arm 19, the construction of the arm being such that the minute hand will move over the dial 22 of the mechanism or clock, in proximity to the markings 23 on the dial indicating minutes.

35   At the opposite end of the case or housing, is a pulley 24 mounted on the shaft 25, the pulley 24 being also formed with a peripheral groove in which the cable 26 moves, the cable 26 having one of its ends secured to the periphery of the pulley 24. The opposite end of the cable 26 has connection with the base 20, as at 27, the cable 26 moving through the guide of the bracket 28. A spring indicated at 29 has one of its ends secured to the shaft 25, the opposite end thereof being secured to the pulley, so that as the cable 16 is wound on the pulley 14, the cable 26 will operate to rotate the pulley 24 in a direction to wind up the spring and put tension on the pulley 24. It is obvious that as the cam 9 rotates and movement is imparted to the pulley 14 to wind the cable 16 thereon, the minute hand 21' will be moved indicating the minutes. When the lever 10 moves to a position where the right angled end or finger 12 thereof moves over the shoulder

30, the bell-crank lever will be snapped over the shoulder, due to the action of the spring 29, unwinding. It will be obvious that the minute hand will now be returned to the left hand end of the case or housing, and that upon further rotary movement of the cam, the bell-crank lever 10 will operate to again wind the cable 16 on the pulley 14, returning the minute hand across the markings of the dial indicating the minutes of the hour.

Associated with the cam 9, and mounted on the shaft 8, is a cam 31 that rotates with the shaft 8. The reference character 32 indicates a bell-crank lever that has one of its arms formed with a laterally extended finger 33 that rests on the periphery of the cam 31. A shoulder 34 is formed on the cam 31, so that the bell-crank lever will drop over the shoulder and contact with the periphery of the cam, after the cam has made one complete revolution. The bell-crank lever 32 has connection with the link 35 that connects with the lower end of the segmental gear 36 which in turn is in mesh with the gear 37 secured to the hub of the pulley 38.

A cable indicated at 39 rests in the peripheral groove of the pulley 38 and is secured thereto. The cable 39 extends through the guide 40 and connects with the base 41 on which the arm 42 is mounted, the arm 42 providing a support for the hour hand 43. The base 41 is formed with bores to accommodate the parallel guide rods 44, so that the base 41 may move freely over the rods with the minimum amount of resistance.

A cable indicated at 45 is connected with the base 41 and moves through the guide 46, the cable being connected to the pulley 47 mounted within the housing. The pulley 47 is supplied with a coiled spring 48 which is wound within the pulley, as the base 41 is moved to the right hand end of the case or housing 5, placing the spring under tension. Thus it will be seen that when the finger 33 moves over the shoulder 34 of the cam 31, the spring 48 will act to rotate the pulley 47 causing the base 41 and hand 43 supported thereon, to be returned to the left hand end of the dial. It will of course be understood that there are certain graduations on the dial over which the hand 43 moves, indicating twelve hours of the day.

In view of the fact that the cam 31 is mounted on the hour hand shaft of the clock mechanism with which the device is used, it is obvious that the cam will make one complete revolution every twelve hours whereupon the mechanism will operate to return the hand 43 to its initial position.

The same may be said for the cam 9, with the exception that the cam 9 being mounted on the minute hand shaft of the clock or timepiece, will rotate at a faster rate of speed, and the hand 21' will move the entire length of the dial and be returned to its initial position, every sixty minutes.

From the foregoing it will be seen that due to the construction shown and described, a rectangular case or housing may be used in conjunction with the usual clock mechanism, converting the usual clock mechanism, wherein the hands thereof rotate over a dial, into a time-piece wherein the hands move longitudinally of the dial, rendering the clock easily read. It will also be seen that because of the rectangular construction of the housing, the device may be used to an advantage on instrument boards of motor vehicles, aeroplanes or the like, the structure of 75

the mechanism being in keeping with the elongated structure of the instrument board.

What is claimed is:

1. The combination with the minute and hour hand shafts of a clock mechanism, of a device for determining time, comprising a casing in which said clock mechanism is mounted, an elongated dial within the casing, minute and hour hands mounted within the casing, means for moving the hands across the dial indicating time, said means comprising cams secured on the minute and hour hand shafts, pulleys within the casing, cables secured to the pulleys and adapted to wind thereon, gears adapted to rotate certain of the pulleys, levers and links operated by the cams and adapted to rotate the gears and pulleys in one direction, and means for operating the cables returning the hands to their initial positions.
- 5 2. In a device of the character described, a casing, an elongated clock dial mounted within the casing, a clock mechanism including hour and minute hand shafts, mounted within the casing, cams secured to the shafts to move therewith, said cams having offset portions in the peripheries thereof, bell crank levers mounted within the casing and engaging the peripheries of the cams, said cams moving the levers when the cams rotate thereunder, pairs of pulleys mounted within the casing, and comprising drive pulleys and driven pulleys, gearing adapted to transmit movement of the driven pulleys to said bell crank levers, a coiled spring in each drive pulley and adapted to rotate said pulleys in one direction when said bell crank levers move onto the offset portions of the cams, cables operating between the pulleys of each pair and adapted to be wound from one pulley to another, and hands movable over the dial and having connection with the cables to move therewith, indicating time.
- 10 3. In a device of the character described, a casing, an elongated clock dial mounted in the casing, rotary hour and minute shafts in the casing, cams secured on the shafts, pairs of pulleys mounted within the casing, each pair of pulleys comprising a spring operated drive pulley and a driven pulley, a horizontally movable cable secured to the pulleys of each pair and adapted to wind thereon, hands connected with the cables and adapted to move longitudinally of the dial when the cables wind from one pulley to another, means for transmitting movement of the cams to the pulleys, said means comprising bell crank levers with which the cams engage, links connected with the bell crank levers, and gearing operated by said links.
- 15 4. In a device of the class described, a casing, an elongated clock dial mounted in the casing, rotary hour and minute shafts in the casing, cams secured to the shafts, pair of pulleys mounted within the casing, each pair of pulleys comprising a spring operated drive pulley and a driven pulley, cables secured to the pulleys and adapted to wind thereon from one pulley to the other, hands connected with the cables and adapted to move longitudinally of the dial when the cables wind from one pulley to another, means for transmitting movement of the cams to the pulleys, said means comprising bell crank levers with which the cams engage, links connected with the bell crank levers, and gearing operated by said links, whereby the pulleys are rotated.
- 20 5. In a device of the character described, a

casing, an elongated dial mounted within the casing, a clock mechanism mounted within the casing, a minute hand shaft and an hour hand shaft mounted on the clock and extending into the casing, rotary cams mounted on the shafts, cables, pulleys on which the cables are wound, brackets secured within the casing, guide members operating within the brackets, base members having bores to receive the guide members,

5 whereby the base members move longitudinally of said guide members, said base members being connected to the cables, indicating hands supported by the base members, said cables adapted to be wound on the pulleys moving the cables and base members, and means operated by said cams for operating the pulleys to wind the cables thereon.

OTTO H. MASER.
